BY George H. Phinney

ATTORNEY.

UNITED STATES PATENT OFFICE.

WILLIAM GARRETT, OF PITTSBURG, PENNSYLVANIA.

ROLLING-MILL FOR WIRE RODS.

SPECIFICATION forming part of Letters Patent No. 320,237, dated June 16, 1885.

Application filed April 6, 1885. (No model.)

To all whom it may concern:

Be it known that I, WILLIAM GARRETT, a citizen of the United States, residing at Pittsburgh, in the county of Allegheny and State of Pennsylvania, have invented or discovered 5 certain new and useful Improvements in Rolling-Mill Plants, of which improvements the following is a specification.

In the accompanying drawings, which make 10 part of this specification, Figure 1 is a plan view of my continuous rolling-mill plant. Fig. 2 is a front elevation of the billet-train. Figs. 3 and 4 are front elevations of parts of the rod-train.

15 The object of my invention is to so arrange the rolls composing my improved plant and to so connect the successive pairs of rolls that the operation of the plant will be entirely automatic from that point in the operation where 20 the bloom has been sufficiently reduced in cross-section to permit of its being fed by "doubling in" up to that point where the bar or rod becomes so small and pliable as to render the action of the turning or twisting and 25 guiding devices uncertain.

The rolls composing a plant have heretofore 30 been arranged either in a common line of feed or else with their axes in line with each other. In the first arrangement each succeeding pair of rolls must have an increase of speed proportionate to the amount of reduction in the preceding pair of rolls, and as in such a train there can be no provision made for what is 35 termed "looping out" the adjustments of the rolls as to speed and reduction must be carefully maintained at all times. In the second arrangement mentioned—*i. e.*, the rolls with their axes in line with each other—it is customary to provide each alternate pair of rolls 40 with grooves adapted to produce an oval rod or bar, the intermediate rolls being constructed to produce square or round bars or rods. The feeding of the bar from one pair of rolls to the next succeeding pair cannot be made automatic on both sides of the line of rolls, as it is not 45 practical to turn or twist an oval rod while passing along a curved guide from one pair of rolls to the next—that is, from a pair of rolls having grooves constructed to produce bars or rods oval in cross-section to a pair of rolls having grooves adapted to produce bars or rods round or square in cross-section. It is

therefore necessary to employ catchers and feeders where the bar or rod is to be changed from oval to square or round.

55 In my improved plant the various pairs of rolls are so arranged that only a part of the plant need be speeded up, as above stated, provision being made for "looping out" the rod as it passes from one pair of rolls to the next, except between such pairs where a turn or twist is given to the passing rod. The steel or iron blooms to be treated are charged into the furnaces A A, located in convenient proximity to the billet-train B, to which they are 60 transferred as soon as properly heated. This billet-train consists of the three-high rolls 1 and the two-high rolls 2, the three-high rolls being provided with suitable grooves for the reduction of the bloom to billet size by a series 65 of back and forth end passes. These rolls 1 should be so constructed as to produce a billet of such a size in cross-section that on its emergence from the last pass it can be fed to the two-high rolls by doubling in; and to effect 70 this feeding of the billet from the last pass of the rolls 1 to the rolls 2 I employ a curved 75 guide, 3. These rolls 1 are driven by an engine, represented at E, the shaft *a* of the engine being provided with a suitable fly-wheel, 80 *b*, and being connected to the shaft of one of the rolls 1, the other rolls being driven by a system of intermeshing gearing, 4, and the rolls 2 are connected by suitable shafts and 85 couplings to the shafts of two of the three-high mill 1. From the rolls 2, which are provided with grooves constructed to produce a bar oval in cross-section, as shown in Fig. 2, the bar or billet is conducted by a suitable trough, 5, to the rolls 6 of the train C. This 90 train C should be located at sufficient distance from the train B to permit of the back and forth passes through the rolls 1 during the reduction of the bloom to billet form, and should be driven at such a speed as to take up the 95 billet as fast as presented by the rolls 2. At any desired point in the trough 5, preferably 100 near the rolls 2, is located the turning or twisting guide 7, adapted to so turn the oval bar or billet emerging from the rolls 2 as to properly present it to the grooves of the rolls 6, the grooves of the rolls 6 being constructed to produce a bar or billet square in cross-section, as shown in Fig. 3. From the rolls 6 the bar or

billet is automatically guided by the curved trough 8 to the rolls 9 of the train C. The rolls 6 and 9 of the train C are driven from the shaft *c*, provided with the gear 10, adapted 5 to intermesh with the gear 11 on the shaft of one of the line of rolls composing the train, and as there is space sufficient to permit the looping out of the bar the rolls 6 and 9 can be driven at the same rate of speed, the 10 trough 8 being so constructed as to permit the loop in the bar to slip over the edge and spread out over the floor of the mill, as represented in dotted lines in Fig. 1. The bar is guided as it leaves the rolls 9, which are provided with 15 grooves adapted to give the bar an oval shape in cross-section, by the trough 12 to the rolls 13 of the train D, which are driven from the shaft *c* through medium of the gears 14 and 15, and as no provision can be made for the looping 20 out of the bar between the rolls 9 and 13 the gears 14 and 15 are so proportioned as to drive the rolls 13 at a higher rate of speed than the rolls 9, proportionate to the amount of reduction and consequent elongation produced by the rolls 25 9. In the trough 12, connecting the rolls 9 and 13, is located a twisting or turning guide, 16, for giving a partial rotation to the oval bar as it leaves the rolls 9, and thereby effecting its proper presentation to the rolls 13, which 30 are provided with grooves suitable for the production of square bars or rods, as shown in Fig. 4. From the rolls 13 the squared rod passes by the curved guide 17 to the rolls 18, forming a part of the train D, said rolls being connected, as shown, to the rolls 13, and driven at a uniform rate therewith, provision being made in the location of these rolls 13 and 18 for the overflow of the rod from the guide 17 and its looping out along the floor of the mill. The rod, 35 as it emerges from the rolls 18, which are provided with grooves suitable for the production of rods oval in cross-section, passes along a trough, 19, provided with a suitable turning or twisting-guide, 20, to the rolls 21 of the train C, said 40 rolls being constructed with suitable grooves adapted to reduce the oval bar properly presented thereto by the trough and turning-guide to a bar square or round in cross-section. These rolls 21 are driven at a speed higher than the 45 speed of the rolls 18 proportionate to the amount of reduction and elongation effected by the rolls 18, through the medium of the gears 22 and 23 from the shaft *c*, said gears being so proportioned as to produce this increase of 50 speed, which is necessary, as there can be no looping out between the rolls 18 and 21, and the bar must therefore be taken up by the rolls 21 as fast as fed thereto by the preceding rolls 18. From the rolls 21 the bar passes by the 55 guide 24 to the grooved rolls 25 of the train C', where it is reduced to an oval shape in cross-section, and thence through the trough 26 and twisting-guide 27 to the rolls 28, composing the train D', said rolls being grooved for the 60 production of rods square or round in cross-section. The rolls 25 are suitably connected to the rolls 21, and are driven at a uniform

rate therewith, the guide 24 being constructed to permit of the overflow of the rod and its looping out along the floor of the mill; but as 70 the rolls 25 and 28 are located in such relation to each other as to preclude such looping out the rolls 28 are driven at a sufficiently increased speed as to take the rod as rapidly as presented by the rolls 25, such increased speed being 75 obtained by properly proportioning the gears 29 and 30, connected, respectively, to the power-shaft *c* and the shaft of one of the rolls 28. From the rolls 28 the bar passes along the curved guide 31 to the rolls 32, having grooves suitably 80 constructed to reduce the bar to an oval shape in cross-section, and as it emerges from the rolls 32 it is directed into the rolls 33 by catchers and feeders, the rod having been reduced to such an area in cross-section and therefore so pliable as 85 to render the action of an automatic feeding and turning guide uncertain. The rod is guided from the rolls 33, which are suitably grooved to reduce the rod to a square shape in cross-section, to the rolls 34 by the curved guide 35, 90 and as it emerges from the rolls 34 it is again directed into the rolls 36 by catchers and feeders. These rolls, from 32 to 36, inclusive, form what I term the "finishing" train D", and the last pair of rolls, 36, are provided with grooves 95 suitably constructed for reducing the rod to a round section. The rod passes from the rolls 36 along the floor of the mill to the reels R R, which are driven at a sufficiently high speed to reel up the rod as fast as it passes from the 100 rolls 36. The main power-shaft *c* is driven by the engine represented at F through the medium of ropes or belts *g*, passing over the fly-wheel *f* of the engine and the pulley *h* on the shaft *c*, and the train D is driven by the engine H through the medium of the ropes or belts *k*, passing around the fly-wheel of said engine and the pulley *l*, suitably connected with said train of rolls.

I claim herein as my invention—

1. In a rolling-mill plant for rolling wire rods, the combination of the billet-train B and the rod-trains C, C', D, and D', each succeeding train being driven at an increased rate of speed as compared with the preceding train 110 proportional to the amount of reduction and consequent elongation effected by the last pass of the preceding train, a finishing-train, D", and suitable troughs or guides between the last pass of one train and the first pass of the 115 next train for conducting, and, except for the last train, turning the bar or rod on its axis, substantially as set forth.

2. In a rolling-mill plant for rolling wire rods, the combination of the trains B, C, D, and C', each train composed of two pairs or sets of rolls, the train D', the rolls of each train being driven at the same rate of speed, but each succeeding train being driven at an increased rate of speed as compared with the preceding train proportional to the amount of elongation effected by the last pass of the preceding train, curved guides for connecting each pair of rolls composing the trains B, C,

D, and C', adapted to permit of the looping out of the rod between such pairs, and a trough and turning-guide between the last pass of one train and the first pass of the next train for conducting and turning the bar on its axis, substantially as set forth.

3. In a rolling-mill plant for rolling wire rods, the combination of the trains B C D C', each composed of two pairs or sets of rolls, the first pair of rolls of each train being provided with suitable grooves for the production of bars square or round in cross-section, and the second pair of rolls of each train having

grooves adapted to produce bars or rods oval in cross-section, a train, D', having grooves 15 adapted to produce an oval bar, a guiding-trough and turning device interposed between the last pass of one train and the first pass of the next train for conducting and turning the bar on its axis, substantially as set forth.

In testimony whereof I have hereunto set my hand.

WILLIAM GARRETT.
